UNITED STATES PATENT OFFICE

161,817

PHONOGRAPH

Roland R. Bollman and John J. Getgey, Cincinnati, Ohio, assignors to Empire Products, Inc., Cincinnati, Ohio, a corporation of Ohio

Application May 20, 1950, Serial No. 10,061

Term of patent 3½ years

(Cl. D56—4)

To all whom it may concern:

Be it known that we, Roland R. Bollman, a citizen of the United States, residing at Cincinnati, in the county of Hamilton and State of Ohio, and John J. Getgey, a citizen of the United States, residing at Cincinnati, in the county of Hamilton and State of Ohio, respectively, have invented a new, original, and ornamental Design for a Phonograph, of which the following is a specification, reference being had to the accompanying drawing, forming a part thereof.

Figure 1 is a top plan view of the phonograph, showing our new design.

Figure 2 is a side elevational view thereof.

Figure 3 is a side elevational view which is turned 90° from Figure 2.

We claim:

The ornamental design for a phonograph, substantially as shown.

ROLAND R. BOLLMAN.
JOHN J. GETGEY.
